UNITED STATES PATENT OFFICE.

DAVID HOMER HAYDEN, OF NEW YORK, N. Y.

REINFORCEMENT FOR COMPOSITION COVERING OF STRUCTURAL METAL SHAPES.

1,121,558.

Specification of Letters Patent. Patented Dec. 15, 1914.

Application filed August 31, 1911. Serial No. 647,103.

To all whom it may concern:

Be it known that I, DAVID HOMER HAYDEN, a citizen of the United States, and a resident of New York, county and State of New York, have invented certain new and useful Improvements in Reinforcements for Composition Covering of Structural Metal Shapes, of which the following is a full, clear, and exact description.

10 The improvement relates to reinforcements for the concrete and like composition covering of structural metal shapes.

15 The invention seeks to provide a simple, inexpensive reinforcement which can be readily and easily applied to structural members and secured thereto in definite or predetermined offset relation, whereby the concrete covering is effectively reinforced and secured to the structural member.

20 The invention consists in the features of improvement hereinafter set forth, illustrated in the preferred form in the accompanying drawings and more particularly pointed out in the appended claims.

25 In the drawings, Figs. 1, 2 and 3 are plan views illustrating different ways of manufacturing the improved reinforcement. Fig. 4 is a sectional view of the I-beam with the reinforcement applied thereto. Fig. 5 is 30 an inverted plan view of the parts shown in Fig. 4. In Figs. 4 and 5 a portion of the reinforcement is expanded and a portion is unexpanded to illustrate the manner in which it is applied to the beam. Fig. 6 is 35 a perspective view of the I-beam with the reinforcement and the concrete covering applied thereto. Fig. 7 is a perspective view illustrating a modified form of the reinforcement and its application to a column.

40 Figs. 8 and 9 are a horizontal section and an elevation, illustrating the application of the reinforcement to an angle-bar. Fig. 10 is a perspective view, illustrating the application of the reinforcement to a channel-bar. Fig. 11 is a section illustrating a modified form.

45 The improved reinforcement comprises an expansible metal strip which is formed of a series of cross-stays 11 each of which is 50 connected to the adjacent cross-stays of the series and which are adapted to extend back and forth over the face of the structural shape or member to which the reinforcement is applied. The strip is provided with 55 a series of offset attaching and spacing elements which secure the same to the struc-

tural member in proper offset relation. As shown, the attaching hooks 12 and spacers 13 are integral with and extend from the points of connection between the adjacent cross-stays 11. Before the expansible reinforcement is applied to a structural member, the series of cross-stays 11 are substantially parallel to one another, as shown at the lower portion of Fig. 5, and the space 60 between the hooks 12 at opposite sides of the reinforcements is somewhat larger than the flange or portion of the structural shape to which it is applied. When the strip is expanded longitudinal of the structural member it is contracted laterally and the hooks are drawn together and engage the flange or flanges of the structural member 70 while the cross-stays are separated and then extend back and forth in zig-zag fashion 75 between the hooks 12 and over the face of the structural member.

Figs. 4, 5 and 6 illustrate the application of the improved reinforcing strip to an I-beam 14. In Figs. 4 and 5 the reinforcing strip is shown partially in its expanded and partially in its unexpanded condition. As there shown, the hooks 12 are adapted to overlap the lower flange of the I-beam 14, while the upwardly and inwardly extending spacers 13 engage the lower face of the flange of the I-beam. The hooks 12, in the unexpanded condition of the reinforcement, can be readily slipped over the flange 80 and as the latter is expanded, drawn tightly 85 and securely into engagement therewith. It is obvious that the engagement of the hooks 12 with the flange limit the expansion of the reinforcing strip, and the engagement of the spacers 13 with the lower side of the 90 I-beam positively position the cross-stays 11 in definite or predetermined offset relation with reference to the face of the beam to thereby securely lock the concrete covering 95 thereto.

100 The improved reinforcement may be formed, as shown in Fig. 1, of a series of wires which are bent to cross each other at the points *a* and are twisted, soldered or otherwise suitably secured together at such 105 points. The portions of the wires between the joints *a* form the cross-stays 11 and the ends of the wires beyond the joints are bent to proper shape to form the offset hooks 12 and the spacers 13. The reinforcing 110 strip is also readily made from a piece of sheet metal, as shown in Fig. 2, by cutting

alternate long and short slots b and c in the opposite edges thereof, to thereby form the connected cross-stays 11 and end extensions which are bent to form the attaching hooks 12 and the spacers 13. Or, as indicated in Fig. 3, the reinforcement could be formed from a piece of expandible metal having slits b' and c' therein. By varying the dimension X, indicated in Figs. 1, 2 and 3, the number of cross-stays 11 per lineal foot may be controlled, as desired, and by varying the dimensions Y, the lengths of the extensions can be controlled and the improved reinforcement adapted to fit different sizes and shapes of the structural members.

Fig. 7 illustrates the application of the improved reinforcement to a column formed of two channel-bars 16 and connecting side plates 17. In this form the cross-stays 11' are centrally connected at points a' as well as being connected at their ends so that the concrete covering will be securely held in place, even though the surface of the column be of considerable width.

Figs. 8 and 9 illustrate the application of the improved reinforcement to an angle-bar 18. In this form, the cross-stays 11'' are bent intermediate their ends to extend around the corner of the angle-bar and certain of the extensions 13', which constitute spacers in the form shown in Figs. 4 and 5, are projected beyond the flanges of the angle-bar to reinforce the body of concrete 19 in which the angle-bar is embedded.

Fig. 10 illustrates the application of the improved reinforcement to a channel-bar 20. In this form the attaching hooks and spacers at one side of the strip are similar to those shown in Figs. 4 and 5 and are arranged to engage the opposite faces of the lower flange of the channel-bar. The joints between the cross-stays 11 at the other side of the reinforcement are each provided with a single extension which is bent upwardly over the face of the channel-bar and around the upper flange, being provided with an inwardly offset portion 13'' to form a spacer and being also provided with a hook 12' 50 which is adapted to engage the upper flange of the channel bar. In the form shown in Fig. 11, the hooks 12'' are provided with upturned end portions 21 and the spacers 13'' extend outwardly beyond the flange of the I-beam 14 to more effectively reinforce the concrete covering 15.

In the present improved reinforcement the connections or joints between the expandible portions or cross-stays are removed from the outer ends of the attaching elements so that the force employed in expanding the reinforcement is transmitted from one part to another without expanding or materially destroying the flange-engaging portions of the attaching elements. Because

of this, the engagement of the attaching elements with the flanges of the structural member will limit or arrest the expansion of the reinforcement with the reinforcing elements thereof uniformly spaced. Thus by 70 properly proportioning the parts, the desired amount of reinforcement per lineal foot can be accurately predetermined. Moreover, the spacing elements or parts of the reinforcement which engage the outer face 75 of the structural member prevent the reinforcing elements thereof from being drawn in against the beam and thus aid in limiting the expansion and in effecting the proper uniform spacing of the reinforcing 80 elements from one another, and from the face of the beam. It should also be noted that, when the reinforcement is applied to the structural member, the attaching and spacing elements and the connections between the cross-stays coöperate to securely 85 maintain the reinforcing elements, in proper, uniform spaced relation to one another and to the face of the member, and prevent them from being pushed along the 90 beam, tilted up against it or otherwise displaced.

It is obvious that numerous changes may be made in the details set forth without departure from the essentials of the invention 95 as defined in the claims.

Having thus described my invention what I claim as new and desire to secure by Letters Patent, is:—

1. An expandible metal reinforcement for 100 composition covering of structural members, comprising connected or joined portions capable of expansion longitudinally of the member and of contraction laterally thereof, and offset extensions constituting attaching elements arranged to hook over the flanges of the member upon the expansion of the reinforcement to secure the latter thereto, the connections or joints between said expandible portions being removed from 110 the outer ends of said extensions, whereby the force employed in expanding the reinforcement is transmitted from one portion to another without expanding or materially 115 distorting the flange engaging portions of said attaching elements.

2. An expandible metal reinforcement for 120 composition covering of structural members, comprising connected or joined portions capable of expansion longitudinally of the member and of contraction laterally thereof, and offset extensions constituting attaching elements arranged to hook over the flanges of the member upon the expansion of the reinforcement to secure the latter thereto, the 125 connections or joints between said expandible portions being removed from the outer ends of said extensions, said reinforcement having parts arranged to engage the outer face of the member to hold the reinforcing por- 130

tions thereof in predetermined offset relation.

3. A metal reinforcement for composition covering of structural members comprising 5 cross stays each connected or joined to adjacent stays to form an expansible series, and attaching elements extending from the connections or joints between said cross stays and arranged to hook over the flanges of the 10 member to secure the reinforcement thereto, said reinforcement having parts arranged to engage the outer face of the member to hold the reinforcing portions thereof in predetermined offset relation.

15 4. An expansible metal reinforcement for composition covering of structural members comprising a series of cross stays connected or joined against separation at intervals to form a zigzag arrangement of the cross stays 20 when expanded, and extensions from said cross stays constituting attaching elements, the joints or connections between said cross stays being removed from the outer ends of said extensions whereby the force employed in expanding the reinforcement is 25 transmitted from one cross stay to another without expanding or materially distorting said attaching elements.

5. An expansible metal reinforcement for 30 composition covering of structural members comprising a series of cross stays connected or joined against separation at intervals to define an angular zigzag arrangement of the cross stays when expanded and integral 35 extensions from said cross stays constituting attaching and spacing elements.

6. A metal reinforcement for composition covering of structural members comprising cross stays each connected or joined 40 to adjacent stays to form an expansible series, said cross stays having offset extensions bent at their ends to constitute attaching hooks, the joints or connections of said cross stays being removed from the hooked 45 ends of said extensions, and said reinforcement having portions offset from the plane of said cross stays and constitute spacing elements.

7. A metal reinforcement for composition 50 covering of structural members comprising a series of cross stays each connected or joined to the adjacent stays to define an angular zigzag arrangement of the cross stays over the face of the member, said cross 55 stays having integral portions extending from the connections or joints thereof and constituting attaching elements arranged to overlap the flanges of the member to secure the reinforcement thereto and said cross 60 stays having integral portions offset from the plane thereof and constituting spacing elements arranged to engage the outer face of the member to hold the reinforcement in predetermined offset relation.

65 8. A metal reinforcement for composition

covering of structural members comprising a series of cross stays formed of separate wires and each connected or joined to the adjacent stay wire of the series to form an angular zigzag arrangement of the cross 70 stays over the face of the member, said stay wires having integral portions extending beyond the connections thereof and forming attaching hooks for engaging the flanges of the member to secure the reinforcement 75 thereto, and stay wires having integral portions forming spacing elements arranged to engage the outer face of the member to hold the reinforcement in predetermined offset 80 relation.

9. A metal reinforcement for the composition covering of structural members comprising an expansible series of connected cross-stays having attaching and spacing elements, said attaching and spacing elements being offset from the plane of the cross-stays and arranged to hook over the flanges and engage the outer faces respectively of the structural member upon the expansion of the reinforcement to secure the 90 latter to the structural member with the cross-stays in predetermined offset relation thereto.

10. A metal reinforcement for the composition covering of structural members comprising cross stays each connected or joined to adjacent stays to form an expansible series, extensions projecting from said cross stays constituting offset attaching hooks, said hooks having parts arranged to abut 100 against the edges of the flanges of the members and said reinforcement having other parts projecting outwardly beyond the flange engaging parts of said attaching hooks. 105

11. A metal reinforcement for the composition covering of structural members embodying an expansible series of cross stays, each connected to the adjacent cross stays of the series, said cross stays having integral 110 portions extending beyond the points of connection thereof and bent to form attaching elements adapted to engage the structural member upon the expansion of the reinforcement to secure the latter thereto, substantially as described. 115

12. A metal reinforcement for the composition covering of structural members embodying an expansible series of connecting cross stays, said cross stays having integral 120 portions extending beyond the points of connection thereof and bent to form attaching and spacing elements adapted to engage the structural member upon the expansion of the reinforcement to secure the latter 125 thereto in predetermined, offset relation, substantially as described.

13. A metal reinforcement for the composition covering of structural members embodying a series of cross stays each connect- 130
